UNITED STATES PATENT OFFICE

2,459,265

MAGNETIC IMPULSE MOTOR

Elmer Keith Crosby, Worcester, Mass.

Application March 22, 1947, Serial No. 736,544

2 Claims. (Cl. 172—126)

1

This invention relates to electric motors of the magnetic impulse type which are particularly designed for use in toys, such as metallic building sets.

It is the general object of my invention to provide a magnetic impulse motor for such purposes which is of improved and much simplified construction; which may be easily and economically manufactured and assembled; which is very easily controlled as to speed and direction of rotation; and which is extremely reliable in operation.

My invention further relates to arrangements and combinations of parts which will be herein-after described and more particularly pointed out in the appended claims.

A preferred form of the invention is shown in the drawings, in which

Fig. 1 is a side elevation of my improved motor; Fig. 2 is a plan view thereof;

Fig. 3 is a plan view of the control switch;

Fig. 4 is a detail sectional view of the switch, taken along the line 4—4 in Fig. 3; and

Fig. 5 is a detail sectional view showing the magnets and associated parts, and taken along the line 5—5 in Fig. 2.

Referring to the drawings, my improved motor comprises a sheet metal base 10 on which a shaft 12 is rotatably supported in bearing plates 14 and 15. The shaft 12 supports a fly wheel 18 and is provided with a crank portion 19 and with a small grooved pulley 20 from which power may be taken off by a suitable cord or belt.

Magnet coils 24 are mounted on a plate 25 secured to a block 26 which in turn is mounted on the base 10. The coils 24 are connected in series, with one terminal 30 connected by a wire 31 to a binding nut 32, and with the other terminal 33 connected by a wire 34 to a U-shaped double contact member 40 having substantially straight contact surfaces 41 and 42. One line wire L is connected to the binding nut 32 and a second line wire L' is connected to a binding nut 44 which is grounded on the base 10.

A rotating contact member 50 is mounted on one end of the shaft 12 and engages one or the other of the surfaces 41 or 42, according to the desired direction of rotation.

The U-shaped double contact member 40 is secured in a slot in a wood block 60 which is tightly threaded on a screw 61 (Fig. 3) secured in the plate 15 by a nut 62. The block 60 is held by friction but may be angularly shifted manually in either direction from the neutral position

2

shown in Fig. 4. In neutral position it stops the motor.

An armature plate 70 is mounted to slide loosely and with a substantially straight-line movement on pin 71 of brass or other non-magnetic material, which are preferably mounted in and coaxial with the cores 72 of the magnet coils 24.

The armature plate 70 is fixed to one end of a connecting rod 75, and the other end of the rod has a direct bearing on the crank 19 of the shaft 12. The holes 77 in the plate 70 are slightly larger than the pins 71, so that a slight rocking movement of the plate 70 is permitted as the crank 19 is rotated and the armature is reciprocated. The line wires L and L' may be connected to a battery or to any convenient source of low voltage D. C. or A. C. electric current.

When the contact member 50 engages one of the contact surfaces 41 or 42, a circuit is completed from the line wire L through the binding nut 32, wire 31 and terminal 30 to the coils 24 and thence through the terminal 33 and wire 34, contact member 40, rotating contact member 50, shaft 12, bearing plate 15, base 10 and binding nut 44 to the line wire L'. The magnet coils are thus energized, attracting the armature 70 and causing rotation of the shaft 12 and fly wheel 18 in the usual manner of magnetic impulse motors.

It will be understood that the magnetic circuit is broken by further rotation as soon as the crank 19 passes horizontal dead center, and that the fly wheel 18 continues rotation of the shaft 12 until the crank 19 has passed the opposite dead center, soon after which the circuit is again closed.

If the switch block 60 is turned so that the surface 41 is engaged by the contact member 50, the fly wheel will be rotated in one direction, and if the contact is between the surface 42 and the member 50, the fly wheel will be rotated in the opposite direction.

Furthermore, the length of the period of contact between the member 50 and the straight contact surface 41 or 42 may be varied by swinging said contact surface toward or away from the axis of the shaft 12. By such changing of the contact period, the speed of rotation of the fly wheel may be varied and controlled.

It thus appears that when this simple control switch is in the position shown in Fig. 4, the motor is at rest, but that both the direction and the speed of rotation may be controlled by simple angular displacement of the block 60 in a selected direction and to a selected extent.

Having thus described my invention and the advantages thereof, I do not wish to be limited to the details herein disclosed, otherwise than as set forth in the claims, but what I claim is:

1. In a magnetic impulse motor, a magnetic unit, an armature mounted to slide toward and away from said unit, non-magnetic and non-magnetized means to support and guide said armature for substantially straight-line movement, a shaft formed with a crank and having a fly wheel mounted thereon, a connecting rod having one end fixed to said armature and having the other end directly pivoted on said crank, and circuit-control means effective to periodically make and break the magnetic circuit.

2. The combination in a magnetic impulse motor as set forth in claim 1, in which the circuit-control means comprises a rotating contact member on said shaft and a control device comprising a pivoted and frictionally supported non-conducting block and a U-shaped contact member having its transverse connecting portion mounted in a transverse slot in said block and

having a pair of substantially straight contact surfaces positioned one at each side of said rotating contact member and engageable thereby as said member is selectively positioned, said control device being effective to control both the direction and the speed of rotation of said shaft by simple manual shifting of said block angularly on its pivoted frictional support, the direction of rotation being controlled by the direction of said angular shift of said block and the speed of rotation being controlled by the extent of said angular shift.

ELMER KEITH CROSBY.
